RIFLE SLING SHOULDER BRACKET

Eugene W. Stephens, 1306 Mifflin St.,
Huntingdon, Pa. 16652

Filed Apr. 10, 1974, Ser. No. 459,691

Term of patent 14 years

Int. Cl. D2—07

U.S. Cl. D2—400

FIG. 1.

FIG. 2.

FIG. 3.

FIG. 4.

FIG. 5.

FIG. 6.

FIG. 1 is a top perspective view of a rifle sling shoulder bracket showing my new design;

FIG. 2 is a top plan view thereof;

FIG. 3 is a bottom plan view;

FIG. 4 is a side elevational view;

FIG. 5 is an end elevational view; and

FIG. 6 is an elevational view of the opposite end.

I claim:

The ornamental design for a rifle sling shoulder bracket, as shown.
